UNITED STATES PATENT OFFICE.

TANEZO OKIHARA, OF HONOLULU, TERRITORY OF HAWAII.

EMBROIDERY-FRAME.

1,302,421.

Specification of Letters Patent. Patented Apr. 29, 1919.

Application filed May 2, 1918. Serial No. 232,099.

To all whom it may concern:

Be it known that I, TANEZO OKIHARA, a subject of the Emperor of Japan, and a resident of the city of Honolulu, county of 5 Honolulu, and Territory of Hawaii, have invented a new and Improved Embroidery-Frame, of which the following is a full, clear, and exact description.

My invention relates to embroidery frames 10 and more particularly to an embroidery frame having rollers to receive the fabric.

An important object of the invention is to provide an embroidery frame of the indicated character, in which the effective size 15 of the frame may be varied to accord with a larger or smaller piece of material to be worked. The said object is attained by providing the side bars of the frame with bearings on their ends to receive the respective 20 rollers, and with intermediate bearings between and distant from the end bearings whereby the rollers may be positioned to turn respectively in the said end bearings or one roller be shifted to the intermediate 25 bearings to thus reduce the effective size of the frame one half or approximately so.

More specific objects of the invention are to provide a ratchet and pawl control for the rollers in either adjustment of the frame, 30 and to provide a knock-down frame including attachable legs that may be readily applied to the frame and variously positionable thereon irrespective of the relative location of the rollers and in a manner that the 35 legs will offer no obstruction when the frame is in actual use.

Reference is to be had to the accompanying drawings in which similar reference characters indicate corresponding parts in 40 all the views.

Figure 1 is a plan view of an embroidery frame embodying my invention;

Fig. 2 is a longitudinal vertical section on the line 2—2, Fig. 1; and

Fig. 3 is a longitudinal vertical section on the line 3—3, Fig. 1.

In constructing a practical embodiment of my invention the frame may be made of any suitable size and of any suitable material.

50 The said frame includes longitudinal side bars 10, 11 and transverse rollers 12, said rollers being of the type having longitudinal strips 13 to clamp the fabric A in slots 14 in the respective rollers. On each roller near 55 an end thereof a ratchet wheel 15 is secured and on the frame bar (10) adjacent to the

ratchet wheels stops 16 are pivoted, as at 17. These stops are laterally movable parallel to the top surface of the frame bar and transversely movable relative to the plane of rotation of the ratchet wheels and are so arranged relative to such ratchet wheels as to be thrown into and out of engagement with the interdental spaces of such ratchet wheels when the rollers 12 are in bearing in 60 the frame bars 10 and 11. These stops 16 are preferably vane shape, having one side shorter than the other, the shorter side being arranged on the inside of the stop, or nearer the ratchet wheel, thereby forming an inclined outer edge where the stop enters the interdental spaces of the ratchet wheels to wedge, stop and lock the ratchet wheels in 65 the desired position. These stops are so arranged that the entering edge of the inclined 70 stop easily enters the interdental spaces of the ratchet wheels, but such inclined edge is so arranged relative to its inclination that the stop cannot completely sweep through the interdental spaces, thereby forming a 75 positive lock against the movement of the ratchet wheel and providing a means for taking up the frictional wear on the stop.

It will be observed that these stops 16 swing in a plane parallel to the upper surface of the frame bars 10; consequently, to release the rollers 12 it is merely necessary to push the shorter side of the stop outward and gradually, not suddenly, release the 80 work from tension, which is a great improvement over the ordinary form of ratchet both 85 in operation and effectiveness.

Another particular advantage of this form 90 of stop is, that owing to its inclined entering edge, the wear upon the abutting parts, 95 that is the interdental spaces of the ratchet wheels, can be compensated.

Bearings are provided at the ends of the frame bars 10, 11 in which the rollers 12 are journaled; the bearings at one end are produced by forming forks 18 on one side bar, as 11, thereby presenting longitudinal slots receiving the journals of the rollers at one end. The opposite side bar (as 10) has transverse holes 10^a therein at each end 100 through which the adjacent journals of the respective rollers are passed, said journals receiving set collars 12^a outside of the bar 10.

In order to adjust or rearrange the frame to reduce the effective size thereof by reducing distance between the rollers 12, I provide in the frame bars 10, 11 intermediate 105

bearings approximately midway between the end bearings in which intermediate bearings one of the rollers may be journaled. The intermediate bearing in one frame bar 10 is 5 in the form of a transverse hole indicated at 19 through which the journal of roller 12 having the ratchet wheel may be passed. The bearing in the opposite frame bar 11 is in the form of a slot 20 which extends down- 10 wardly through the upper surface or top edge of the frame bar and is reentrant or undercut by extending its lower end toward an end of the frame bar. Thus a roller 12 may be journaled in the intermediate bearing by 15 passing one journal through the hole 19 and dropping the other journal into the slot 20. Obviously with one roller in the intermediate bearings the effective size of the frame will be reduced approximately one half, said 20 bearings being about midway between the ends of the side bars. Thus the embroidery frame may be adjusted to suit a larger or a smaller piece of fabric to be worked.

It will be seen that the frame may be dis- 25 assembled by removing the rollers from their bearings. I provide also for the frame, and in conformity with its knock-down character, legs 21 readily attachable and detachable, there being three of such legs, two being disposed beneath one frame bar, as at 30 the left of Fig. 1, and one in a central po-

sition beneath the other side bar. Each leg is formed at its upper end with a fork 21 thereby presenting a slot 22 for receiving the frame bar to which the leg is applied, as the 35 legs may be slipped into position or readily removed.

I would state in conclusion that while the illustrated example constitutes a practical embodiment of my invention, I do not limit 40 myself strictly to the mechanical details herein illustrated, since manifestly the same can be considerably varied without departure from the spirit of the invention as defined in the appended claim. 45

Having thus described my invention, I claim as new and desire to secure by Letters Patent:

An embroidery frame including side bars having bearings, rollers journaled in said 50 bearings and adapted to receive and carry the fabric to be worked, a ratchet wheel on each roller, and stops located on the frame and movable in a lateral plane at right angles to the plane of rotation of the said 55 ratchets and having an inclined outer edge adapted to enter the interdental spaces of the said ratchet wheels, locking said wheels in position and taking up the frictional wear of the abutting parts.

TANEZO OKIHARA.
